METHOD OF MAKING IDENTIFICATION TAGS

Joseph S. Pecker, Upper Darby, Pa., assignor to Dennison Manufacturing Company, Framingham, Mass., a corporation of Massachusetts

Application September 2, 1944, Serial No. 552,467

5 Claims. (Cl. 93—91)

1

This invention relates to a shipping or identification tag or the like having two cords, strings or wires permanently secured to the tag, the cords, strings or wires extending beyond one end of the tag for a suitable distance. In use, the tag may be readily connected to packages or articles by inserting one of the cords, strings or wires through some part of the package or article, and thereafter tying or twisting the ends of the two cords, strings or wires together. More particularly, the invention relates to the manner or process by which the two cords, strings or wires are secured to the tag and the resulting tag as an article of manufacture.

The usual shipping or identification tag comprises a piece of relatively stiff paper, cardboard, or the like, having a single aperture at one end thereof, the aperture being reinforced with annuli encircling the aperture on both faces of the tag, and two wires, strings or the like extending from the aperture so that the tag may be secured to an object by twisting or tying the ends of the strings or wires about an object.

The present manner of securing wire or strings to identification tags is to insert one end of the string or wire through the aperture within the tag and thereafter tie the ends of the strings or wires in one form or another, or, if wire, twist the wire beyond the tag so that the wire will not pull loose therefrom. Heretofore it has required considerable skill, either manually or by complicated machinery, to thread the string or wire through the aperture of the tag and thereafter tie the string or twist the wire beyond the end of the tag to prevent it from becoming loose. It is a slow and tedious process to tie string or wire by hand and therefore quite expensive. While machines are now in use for accomplishing this purpose, the machines are quite complicated and costly, thereby increasing the cost per tag unit as well as involving a considerable initial outlay of capital. The difficulty of thus preparing identification tags in large numbers having string or wire attaching means inexpensively will at once be apparent.

The present invention obviates the problems heretofore experienced of attaching string, cord or wire to the tags, yet by practicing the present invention, the strings or wires are secured to the tags in a secure and satisfactory manner, and by a continuous process, if desired, the process being carried out either by hand or by machine.

By practicing the present invention, individual identification tags may be formed having attaching means secured thereto in a more expedient

2

manner and without the necessity of using complicated machinery.

The main object of this invention is to secure cords, strings or wires to identification tags wherein the former functions as a means for holding the tag to an object.

Another primary object is to provide a process wherein the necessity of tying or looping the strings or wires through the aperture within the tag by complicated machinery, or by hand, is eliminated.

Another object of the invention is to secure strings, cords or wires to identification tags by a continuous process, if desired.

Still another object of the invention is to secure strings or wires to identification tags wherein the strings or wires extending from the tag may be of any desired length.

Another object of the invention is to so secure the wire as to increase the area of the metal in contact with the edge of the hole to reduce the tendency to tear through the loop, therefore increasing the strength of the tag where it is important with or without the use of eyelet reinforcement.

Other and further objects of the invention will be obvious to those skilled in the art, a preferred embodiment of the invention being shown in the accompanying drawings, which are made a part hereof, wherein

Figure 1 is a side view showing an intermediate step of the method of securing the strings or wires to identification tags;

Figure 2 is a central longitudinal sectional view of Figure 1 showing the wires or strings in elevation, and

Figure 3 is a perspective view of a single tag after it has been formed by the invention forming the subject matter of this invention.

In the drawings, the reference numeral 10 generally indicates the usual identification tag having an aperture 11 adjacent one end of the tag. The usual reinforcement annuli 12 is glued, or otherwise secured on both sides of the tag to reinforce the aperture 11, so that the string or wire will not tear or otherwise pull loose from the tag.

One manner of practicing the invention is to place the tags 10 in alignment, as shown in Figure 1 of the drawings, so that the apertures 11 extend in substantially the same direction. Preferably, the tags are spaced from each other, although, as will hereinafter be explained, it is not essential to have any appreciable space between the tags.

If the process is to be practiced manually, and it is desired to have wire, metallic ribbon or the

like as the attaching means for the tags, then one of the easiest procedures is to place a long wire, metallic ribbon, or the like, 13, on a suitable support, after which the tags 10 are placed over the wire or ribbon 13 so that the apertures 11 in the tags overlie the wire or ribbon. Thereafter, a long wire, ribbon, or the like, 14, is placed over the tags 10 so that the same overlies the apertures 11 and the wire or ribbon 13. After the two wires or ribbons 13 and 14 and the tags 10 are positioned in such manner, the wires or ribbons are welded or otherwise fused together at a point where they overlie the apertures 11, as clearly illustrated in the drawings. The next step is to weld or fuse the wires or ribbons 13 and 14 together at a point beyond the ends of the tags, also as clearly shown in the drawings. It will be understood, of course, that the weld between the tags may be performed prior to the first mentioned welding, or the two welding operations may take place simultaneously.

After the completion of the foregoing step or steps, the ribbons or wires and tags take the form as shown in Figures 1 and 2 of the drawings. Thereafter the two wires or ribbons 13 and 14 are cut or severed at a point where they overlie the apertures 11, such point being below the weld within the aperture. The cut-off point is clearly illustrated in Figure 1 of the drawings. Thus, a portion of the wires or ribbons 13 and 14 which overlie the intermediate tag as shown in Figure 1 becomes the attaching portion for the lowermost tag. For example, it can be assumed that the tag shown in Figure 3 is the lowermost tag shown in Figure 1, and that the wires or ribbons 13 and 14 of the completed tag had previously extended on each side of the major portion of the intermediate tag shown in Figures 1 and 2.

If it is desired to have cords, strings or other non-metallic elongated elements as the tag attaching means, the process is performed in a manner similar to that previously mentioned. However, instead of the welding operation, the cords or strings are secured together at the two points previously mentioned, i. e., at a point within the aperture of the tag and at a point just beyond the apertured end of the tag, by using a quickly setting glue, preferably a phenolic or resinous glue. If the glue or resinous bonding agent is of the thermo setting type, it is desirable to dry the glue quickly by applying heat. The heat may be applied locally to the bonding points, or the entire tag and string assembly may be heated. The only essential requisite is that the heat be applied, of course (if at all), after the tags and cords or strings are positioned as aforementioned and after the glue has been applied.

It will be obvious, of course, that the process may be modified in several ways without departing from applicant's invention. For instance, it is not necessary to first place one wire or string on a support and thereafter position the tags in spaced relation over the first wire or string and then place the second wire or string on top of the tags. The tags may be positioned in any suitable manner and the two wires or strings may be positioned relative to the tag, one after another or simultaneously, so long as the two wires or strings extend over the apertures of the various tags.

The space between the top end of one tag and the bottom end of the next tag may, of course, be varied at will depending upon the desired length of the wires or strings extending from the individual tags. For instance, if the shape of

the tags were varied from that shown in the drawings so that their length is considerably longer, it would probably be desirable to lessen the space between the tags. Conversely, if the tags were considerably shorter than those shown in the drawings it would probably be advisable to increase the space between the tags so that the attaching strings or wires may be of a suitable length for accomplishing their intended function.

10 Furthermore, the process may be suitably performed by placing the tags side-by-side, rather than end-to-end as shown in the drawings, so long as the apertures in each tag extend in substantially the same direction relative to the tag proper. In such latter alignment of the tags, the wires or strings will also be placed so as to overlie each side of the aperture in the tags and the aforementioned steps of welding, bonding, fusing or gluing and cutting or severing are subsequently performed.

There may be various other detailed ways of positioning the tags and the wires or strings with respect thereto, and the process disclosed herein performed, so long as wires, elongated metallic elements, cords or strings are positioned on each side of the tags so that the elongated elements overlie each of the apertures in the tags, after which the elongated elements are welded, fused, bonded or glued together at a point within the aperture and a second point located elsewhere than within the aperture so that the two elongated elements are securely fastened to the tag. Thereafter, the elongated elements must be severed at a point below the point of fusion or bonding within the aperture so as to form separate individual tags.

The terms "fuse," "fusing," "fusion," etc., mean generally to unite, blend or combine by the application of heat, to melt two elements, usually 40 metals, to cause the metals to unite or run together. In this application, and particularly in the claims, the terms include not only this generally accepted meaning but also (for lack of a better term) the uniting or securing together by means of a bonding agent, glue, or the like, with or without heat. Also, the term "wire" as used in the claims includes any elongated metallic elements, such as flat ribbon, round wire or the like, regardless of the cross-sectional shape thereof.

55 From the foregoing it will be evident that the strand means, whether formed of cord, string or wire, has strand portions extending along opposite sides of each tag from the location of the aperture to a location at the adjacent edge of the tag, the strand portions being integrally interconnected at both locations and at least one and preferably both of the interconnections being formed by fusing the two portions together after they are applied to the tag.

60 I claim:

1. In making tags of the type having an aperture and strand attaching means extending through the aperture with portions of strand extending along opposite sides of the tag from the location of the aperture to a location at the edge of the tag, the method which comprises holding said strand portions along opposite sides of the tag and fusing the two portions together at both of said locations.

70 2. In making tags of the type having an aperture and strand attaching means extending through the aperture with portions of strand extending along opposite sides of the tag from the location of the aperture to a location at the edge of the tag, the method which comprises

holding two strands along opposite sides of a row of tags approximately in a plane intersecting said locations of each tag of the row, fusing the two strands together through each aperture, and then severing each strand at the side of each aperture opposite said edge of the corresponding tag.

3. In making tags of the type having an aperture and strand attaching means extending through the aperture with portions of strand extending along opposite sides of the tag from the location of the aperture to a location at the edge of the tag, the method which comprises holding two strands along opposite sides of a row of tags approximately in a plane intersecting said locations of each tag of the row, fusing the two strands together through each aperture and near each of said edges, and then severing each strand at the side of each aperture opposite said edge of the corresponding tag.

4. In making tags of the type having an aperture and strand-attaching means extending through the aperture with portions of strand extending along opposite sides of the tag from the location of the aperture to a location at the edge of the tag, the method which comprises holding separate strands along opposite sides of the tag respectively so that portions of said strands are juxtaposed at said aperture and fusing said juxtaposed portions together.

5. In making tags of the type having an aperture and strand-attaching means extending through the aperture with portions of strand extending along opposite sides of the tag from

the location of the aperture to a location at the edge of the tag, the method which comprises holding separate strands along opposite sides of the tag respectively so that portions of said strands are juxtaposed at both said locations, fastening said juxtaposed portions together at said aperture and fusing said juxtaposed portions together beyond said edge.
